UNITED STATES PATENT OFFICE.

JOSEF HREN, OF BROOKLYN, NEW YORK.

RULING DEVICE.

SPECIFICATION forming part of Letters Patent No. 752,556, dated February 16, 1904.

Application filed October 29, 1903. Serial No. 179,094. (No model.)

To all whom it may concern:

Be it known that I, JOSEF HREN, a citizen of the United States, residing at Brooklyn, in the county of Kings and State of New York, have invented new and useful Improvements 5 in Ruling Devices, of which the following is a specification.

By means of this invention adjustment can readily be made for ruling such number or arrangement of lines as may be called for.

This invention resides in novel features of constructions as set forth in the following specification and claim, and illustrated in the annexed drawings, in which—

15 Figure 1 shows a front elevation of the ruling device. Fig. 2 is a sectional front elevation of Fig. 1. Fig. 3 is a section along $\alpha\alpha$, Fig. 2. Fig. 4 is a section along $\gamma\gamma$, Fig. 2. Fig. 5 shows a modification. Fig. 6 is a section 20 along $z z$, Fig. 5.

The ruling-roller consists of a series of rails or tracks on which are mounted a number of diskiform rulers adapted to be set in any desired position along the said rails, and the rails 25 being engaged by a series of expanders the diskiform rulers can be rigidly clamped to the rails.

The bearing-roller is provided with a number of coiled-wire springs which can be set 30 on the roller to register with the diskiform rulers.

In the drawings is illustrated a ruling-roller a and a bearing-roller b . The ruling-roller a is of skeleton form and is provided with journals $c c$, having cylinder-heads $d d$. These cylinder-heads are provided with a number of slots e , in each of which is guided an expander f and a rail or track g . An end of each of the expanders f is screw-threaded and engaged 35 by a nut h , which is prevented from moving longitudinally by a disk i . On the rails g are mounted a series of rings or diskiform rulers j , and these rings can be slid longitudinally along the rails and placed in any desired position between the cylinder-heads $d d$. Each expander f is tapered or wedge-shaped and engages with the tapered part of the track or rail g and when the nut h is turned it moves 45 each of the expanders longitudinally to spread each of the expanders longitudinally to spread 50 or contract the radius and diameter of each

of the rails, thereby clamping or loosening the diskiform rulers. The bearing-roller b is provided with grooves k , which serve as rests for a number of coiled-wire springs l . The springs or elastic rings can be set any desired 55 position apart on the bearing-roller, so that the springs and the ruling-flange of the diskiform rulers will register. A spring or ring l at each side of a ruling-flange or ruler has been found to give a support for ruling or 60 drawing a clean or sharp line. The rings and coiled springs can be set to any desired spacing or relation, and the rings and springs not to be used can be slid or set to one side or out of the way. When spaced or adjusted and 65 clamped by the action of the expanders on the rails, the rings are held in position.

The number of rails and expanders is of course not limited to four or any specific number; but the device shown has been found to 70 work satisfactorily.

The device can be modified. The expander instead of being wedge-shaped or tapered can be provided with seats for balls m , Fig. 5, and such ball-carrying expanders f' can be 75 set longitudinally or screw-adjusted, as already stated. The rails having concave or inclined seats or faces at the balls m and the latter acting against or moving toward a shallow part of these seats as the expander is being adjusted the rails will clamp the ruler-rings, as before. The setting back and forth of the expander will thus spread the rails or allow them to come together or move toward the center or axis of the roller to clamp or un-clamp the rulers.

The device is not confined to the precise structure shown, as modifications can be made which are included in the invention. The expanding or expandable rail can be rapidly set 80 or loosened by the longitudinally-movable expanders.

What I claim as new, and desire to secure by Letters Patent, is—

1. A ruling device comprising ruling rings 95 or disks, rails for the disks and expanders for the rails movable relative to said rails.

2. A ruling device comprising ruling rings or disks, expandable rails and longitudinally-movable expanders.

3. A ruling device comprising ruling rings or disks, rails for the disks and longitudinally-movable expanders with set-screw for expanding and clamping the rails to the rings.
- 5 4. A ruling device comprising a cylinder having heads, rails made to move radially but not longitudinally in the heads, expanders made to move longitudinally in or through the heads, and a screw or adjusting nut mounted 10 to rotate in a fixed plane and made to engage or adjust the expanders.
- 15 5. A ruling device comprising a ruling-roller having rings, expansible rails for clamping or fixing the rings, expanders for the rails and a grooved bearing-roller having spring or elastic rings which can be set along the roller into grooves.
- 20 6. A ruling device comprising adjustable rings or rulers with a bearing-roller having elastic or spring rings adapted to be set in conformity to the rulers.
7. A ruling device comprising rings or rulers, rails for the rulers provided with in-

clines, and expanders made to set against the incline of the rail, the latter being movable longitudinally and independently of the rings and expanders.

8. A ruling device comprising ruling-rings, supports for said rings radially adjustable relative thereto, and means for adjusting said supports to said rings for clamping the same.

9. A ruling device comprising adjustable ruling-rings, supports radially adjustable relative to said rings, longitudinally-movable members for adjusting said supports, and means for moving said members relative to said supports for clamping and unclamping said rings.

In testimony whereof I have hereunto set my hand in the presence of two subscribing witnesses.

JOSEF HREN.
